UNITED STATES PATENT OFFICE

153,857

DESIGN FOR A STAND FOR COFFEE MAKER

John E. Comeau and Harry C. Mitchell,
Kansas City, Mo.

Application July 19, 1947, Serial No. 140,390

Term of patent 3½ years

(Cl. D44—26)

To all whom it may concern:

Be it known that we, John E. Comeau and Harry C. Mitchell, citizens of the United States, residing at Kansas City, in the county of Jackson and State of Missouri, and Kansas City, in the county of Jackson and State of Missouri, respectively, have invented a new, original, and ornamental Design for a Stand for Coffee Maker, of which the following is a specification, reference being had to the accompanying drawing, forming a part thereof.

Fig. 2 is an end elevation of the stand for coffee maker.

Fig. 3 is a plan view of the stand.

We claim:

The ornamental design for a stand for coffee maker, as shown.

JOHN E. COMEAU.
HARRY C. MITCHELL.
